Primary Examiner — Eliza Z Harvey*Assistant Examiner* — Kayla Marie Bennett(74) *Attorney, Agent, or Firm* — Ying-Ting Chen; Law Office of Michael Chen(57) **CLAIM**

The ornamental design for a hose reel, as shown and described.

DESCRIPTION

FIG. 1 is a perspective view of the hose reel showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view of thereof; and

FIG. 7 is a bottom plan view of thereof; and,

FIG. 8 is an enlarged view of portion 8 shown in FIG. 1. The dash-dash broken lines shown in FIGS. 1-8 illustrate portions of the hose reel that form no part of the claimed design; The dot-dash broken lines surrounding the detail views shown in FIGS. 1 and 8 are for purposes of annotating the enlarged view only and form no part of the claimed design.

1 Claim, 8 Drawing Sheets(56)
